(57) **CLAIM**

The ornamental design for a decorative panel for building, as shown and described.

DESCRIPTION

FIG. 1 is a front view of a decorative panel for building according to my new design;

FIG. 2 is a left side view thereof;

FIG. 3 is a bottom perspective view thereof;

FIG. 4 is an enlarged partial left-side view of the building panel showing the portion within area 4 of FIG. 2;

FIG. 5 is an enlarged, partial front view of the building panel showing the portion within area 5-5 of FIG. 1; and,

FIG. 6 is a front view of the decorative panel thereof shown in a condition of use, with the decorative panel being used in conjunction with a second lightened and broken line decorative panel.

The dot-dash lines of FIGS. 1-4 depict the boundaries of enlargement and form no part of the claimed design. The lightened portion surrounded by broken lines of FIG. 6 illustrates an additional panel that forms no part of the claimed design.
